WEDDING DISPLAY ORNAMENT

Ralph J. Kuehnel, 251 S. Zenobia, Denver, Colo.

Filed May 28, 1958, Ser. No. 51,107

Term of patent 7 years

(Cl. D29—1)

FIG. 1 is a front elevational view of a wedding display ornament, showing my new design;

FIG. 2 is a rear elevational view thereof;

FIG. 3 is a top plan sectional view taken along the line 3—3 of FIG. 1, and

FIG. 4 is a side elevational view in reduced scale thereof.

I claim:

The ornamental design for a wedding display ornament, as shown.
